UNITED STATES PATENT OFFICE.

EUGENE F. DAVENPORT, OF MELROSE, MASSACHUSETTS, ASSIGNOR TO
UNITED SHOE MACHINERY COMPANY, OF PATERSON, NEW JERSEY,
A CORPORATION OF NEW JERSEY.

SKIVING-MACHINE.

No. 823,586.

Specification of Letters Patent.

Patented June 19, 1906.

Application filed May 12, 1902. Serial No. 106,978.

To all whom it may concern:

Be it known that I, EUGENE F. DAVENPORT, a citizen of the United States, residing at Melrose, in the county of Middlesex and State of Massachusetts, have invented an Improvement in Skiving-Machines, of which the following description, in connection with the accompanying drawings, is a specification, like reference characters on the drawings representing like parts in the several figures.

This invention relates to a machine for skiving leather, and is shown in the drawings and is herein described as embodied in a machine in which a rotary disk cutter is employed. The cutter is set in such relation to a work-support that as a piece of leather is fed toward the cutter a strip will be cut from the edge of the leather in such a way as to leave said edge skived or beveled.

Many portions of the machine to which the present invention is shown as applied are substantially the same as corresponding parts of the machine shown and described in United States Letters Patent No. 636,942, granted to Charles H. Bayley.

A feature of the present invention consists in providing a high-speed work-feeding mechanism with means by which the operator is enabled to control the rate of feed, whereby work may be advanced rapidly when desired, as when portions thereof having regular edges are being operated upon, and may be advanced more slowly at other times, as when irregular edges are being operated upon.

Another feature of the invention consists in a machine provided with a cutter and a work-feeding device which are actuated normally at predetermined relative speeds, said machine having a connection between the feeding device and its actuating mechanism which will permit the movement of the feeding device to be retarded by resistance applied to the feeding device without changing the speed of the cutter. In the embodiment of the invention herein shown the operator may retard the rotation of the feeding device by holding back the work or by applying his finger as a brake to the feeding device, and thereby vary the rate at which the work is fed relatively to the speed of the cutter.

This provision for varying the rate of feed with relation to the speed of the cutter is of particular value in a skiving-machine when operating upon soft and spongy stock and when skiving pieces of stock the edges of which are irregular.

It has been recognized that it is desirable materially to increase the speed of skiving-machines while operating upon pieces of work having regularly-formed edges in order thereby to increase the capacity of the machine. It has been found, however, that the speed at which the work could be fed in existing machines was in practice limited by the fact that it is necessary in feeding work having irregular edges for the operator to manipulate the work by turning it from side to side to keep the irregular edge against the edge guide. The speed which it was practical to give the machine has therefore been limited and has been dependent upon the skill with which the operator was able to manipulate the pieces of work which had irregular edges. With these facts in mind the present feeding mechanism, which is adapted to be actuated to feed the work very rapidly while operating upon regular edges, has been provided with means by which the feeding of the work may be retarded and completely controlled by the operator while the machine is operating upon irregular edges or the irregular portions of an edge.

In the drawings, Figure 1 is a side elevation of a complete machine. Fig. 2 is a sectional view on line $z-z$ of Fig. 1. Fig. 3 is a plan view of a portion of the machine.

The frame A of the machine is adapted to rest upon a table or other base and is of such shape as to support and guide the movable parts of the machine. The driving-shaft 2 may be actuated from any suitable source of power and is provided at 3 with a worm which engages a worm-gear 4 upon a shaft 5. The shaft 5 actuates the shaft 7 through beveled gears 6 6, and the shaft 7 carries the work-support or lower feeding member 8. A worm 10 on the left-hand portion of the driving-shaft actuates a worm-gear 11, carried by a shaft 12. A feeding-disk 13 is mounted on the lower end of the shaft 12 and is adapted to co-operate with the work-support 8 to feed

the work by engaging the upper surface of the work with its marginal face. A spiral spring 14 surrounds the shaft 12 and bears at its upper end against a shaft-bearing 1^a and at its lower end against an adjustable collar 12^a on the shaft 12. The spring normally presses the feeding-disk 13 down upon the work, which is supported upon the lower feeding member 8, and as said disk and feeding member are rotated the work is fed thereby against a rotary knife, (indicated at 22.) The knife is carried on a shaft 20, mounted in bearings 21, and is adapted to be driven in any suitable manner by the driving-shaft 2. 15 An edge guide is indicated at 60.

The machine as thus far described is the same as that shown in the said Letters Patent.

The feeding-disk shaft 12 is provided near its upper end with a cone comprising a collar 40 and a bushing, upon which is secured the tapering section 42, composed of suitable friction material. The cone is adjustably secured on the shaft 12 by a clamping-screw 41. 20 The cone constitutes one member of a friction-clutch, which clutch is designed to afford between said feeding-disk shaft and the positively-driven worm gear or pinion 11 a connection that will permit the operator to 25 retard the rotation of the feeding-disk shaft by holding back the work or by means of resistance applied to the feeding-disk or its shaft in any manner. The pinion 11 is provided with a suitable socket to receive the 30 cone, and this pinion constitutes the other member of the clutch. A spring 43, bearing at its base upon the pinion 11 and having its upper end connected to the shaft 12 by the screw 44, serves to hold the clutch members 35 in frictional contact. The tension of the spring 43 may be varied by adjusting the cone nearer to or farther from the upper end of the shaft 12. This adjustment of the tension of the spring 43 controls the readiness 40 with which the clutch will slip.

By means of the connection above described between the feeding-disk and its actuator said feeding-disk is normally driven at the same speed as the work-support to feed 50 the work against the skiving-knife. The feeding members may be so connected to the driving-shaft as to rotate at a high speed and feed the work very rapidly to the knife while operating on straight edges. When, however, an irregular edge is reached, the operator is enabled, because of the described connection between the feeding-disk shaft and the driving-shaft, to hold the work back, and thereby cause the feeding-disk to be retarded 55 in order that he may manipulate the work to present the irregular edge properly to the skiving-knife. Instead of holding the work back the feeding-disk may be retarded by the finger of the operator placed lightly upon

it. This capacity of the machine to permit the work to be manually held back is also of advantage in skiving very thin, soft, or spongy leather, as it is necessary to hold such leather taut and allow it to be fed slower than heavier leather may be fed. By reason of 70 the novel arrangement herein described the operator may permit the work to be fed to the knife only so fast as the knife can skive it to the best advantage.

The operation of the machine is as follows: 75 The parts being adjusted to the position shown in Fig. 1 the machine is started by connecting the driving-shaft to the source of power. The workman presents a piece of leather which is to be skived with its edge 80 against the usual edge guide. The rotary work-support and the feeding-disk grasp the leather and rapidly feed it along against the skiving-knife, which trims it in such a way as to form a beveled edge thereon. In skiving 85 a straight or uniformly-curved edge very little guidance of the work by the workman is necessary, and the feeding mechanism may therefore be allowed to advance the work at full speed. When an irregular edge is 90 reached, however, the workman must turn the work from side to side, as is well understood, in order to keep the irregular edge against the edge guide. To enable this to be done, the work must be fed more slowly. 95 The described connection between the feeding-disk and its actuator enables the workman to hold the work back, and thus retard the rotation of the feeding-disk, or he may retard the disk by placing his finger lightly 100 on it. The work is thus drawn into the machine more slowly, allowing the workman time and opportunity to manipulate it to cause it to be presented properly to the skiving-knife. It is to be understood that while 105 the workman retards the feeding-disk the pinion 11 continues to be rotated from the driving-shaft at a uniform speed, and the socket turns with relation to the cone of the feeding-disk shaft or more rapidly than said 110 shaft. This causes the feeding-disk to exert a constant pull on the work, which aids the workman in guiding the work and will cause it to be fed forward again at normal speed as soon as the workman ceases to hold it back 115 or otherwise to retard the rotation of the feeding-disk.

In the foregoing description so much of a skiving-machine has been described as is necessary to disclose this invention fully. It is 120 not intended to limit the invention, however, to the embodiment thereof herein shown, since it may be embodied in other forms without departing from the spirit of the invention. It is also not intended to limit the novel feeding 125 mechanism to use in skiving-machines, as it is obvious that it might be used in machines in which the work is fed to any sort of a de-

vice for operating upon it instead of to a skiving-cutter.

What I claim as my invention, however, and desire to secure by Letters Patent, is—

5 1. In a machine of the class described, a device for operating upon the work, in combination with independent mechanism for feeding the work to said operating device, said work-feeding mechanism comprising a feeding-disk, means to actuate said disk, and a connection between said actuating means and said disk arranged to permit the movement of the feeding-disk to be retarded by resistance applied to said disk and to allow 15 the actuating mechanism to move independently of said disk.

2. In a skiving-machine, the combination, with devices for operating on the work, of feeding mechanism, comprising a work-support, a feeding-disk, and means for rotating the work-support and feeding-disk, said means including a positively-actuated member and a connection between the feeding-disk and said positively-actuated member, 25 constructed and arranged to permit the operator to retard the rotation of the feeding-disk by holding back the work.

3. In a skiving-machine, the combination with a cutter, of mechanism independent of the cutter for feeding the work, said feeding mechanism comprising a work-support and a feeding-disk adapted to coöperate to feed the work, a driving-shaft to actuate said feeding members, and connecting means between said 35 driving-shaft and one of said feeding members, arranged to permit relative movement of said parts and allow the operator to retard the feeding member by holding back the work.

40 4. In a skiving-machine, the combination with a cutter, feeding members coöoperating to advance the stock to the cutter, and positively-driven mechanism for actuating one of said feeding members, of mechanism for actuating the other feeding member constructed and arranged to permit the movement of said other feeding member to be retarded by resistance transmitted through the work being fed.

50 5. In a skiving-machine, the combination, with a cutter, of mechanism independent of the cutter for feeding the work, said feeding mechanism comprising a work-support, a feeding-disk, a driving-shaft, and operative connections between said driving-shaft and the feeding-disk, said connections including a cone-clutch, the members of which are held yieldingly in engagement and are arranged to move relatively to permit the rotation of the feeding-disk to be manually retarded for varying the rate at which the work is fed.

60 6. In a skiving-machine, the combination with a cutter, of a work-support, a driving-

shaft, a feeding-disk shaft and connected 65 with said driving-shaft and carrying a feeding-disk, said feeding-disk shaft comprising two sections provided, respectively, with the members of a cone-clutch, yielding means for holding said clutch members in engagement, and means for adjusting the force of such holding means.

70 7. In a skiving-machine, the combination with a skiving-knife, of a feeding mechanism comprising a driving-shaft, a work-support, 75 a positive connection between said work-support and the driving-shaft to actuate the work-support, a feeding-disk also actuated from said driving-shaft and adapted to co-operate with the work-support to feed the work at a normal speed, and a connection between said disk and the driving-shaft arranged to permit the work being fed to be manually retarded and fed at less than normal speed.

80 8. In a skiving-machine, a driving-shaft, a work-support, a feeding-disk, a shaft on which said feeding-disk is mounted, a pinion on said disk-shaft in operative connection with said driving-shaft, a socket formed in 85 said pinion, a cone-clutch member adjustably mounted on said disk-shaft and adapted to coöperate with said socket in the pinion to actuate the disk-shaft from the driving-shaft, and yielding means for holding said cone in its socket whereby the feeding-disk may be retarded by the operator to control 90 the feeding of the work.

9. In a skiving-machine, the combination with a cutter, a work-feeding roll arranged to support the work and to advance it to the cutter, a coöperating work-feeding disk arranged to engage by its marginal face upon the upper surface of the work, a shaft upon which the disk is mounted, and a driving-shaft, of a connection between the driving-shaft and the feeding-disk shaft whereby the rotation of the feeding-disk may be retarded 100 by resistance applied to the work by the operator while guiding the work.

10. In a machine of the class described, the combination with a device for operating upon the work, of a work-feeding mechanism comprising a feeding member, actuating means therefor, and a frictional connection between the feeding member and the actuating means arranged to allow the movement of the feeding member to be retarded by unusual resistance while the actuating means continues its normal movement.

11. In a skiving-machine, the combination with a cutter, a work-feeding device, and actuating mechanism connected with the cutter and the feeding device to drive said devices normally at predetermined relative speeds, of a connection between the feeding device and said actuating mechanism arranged to permit the movement of the feed-

ing device to be retarded by resistance applied to said device without changing the speed of the cutter.

12. In a skiving-machine, the combination with a cutter, a work-feeding device, and actuating means connected with the cutter and the feeding device to drive said devices normally at predetermined relative speeds, of a frictional connection located between the feeding device and said actuating mechanism

and arranged to allow the operator to retard the movement of the feeding device by holding back the work.

In testimony whereof I have signed my name to the specification in the presence of 15 two subscribing witnesses.

Correction in Letters Patent No. 823,586.

It is hereby certified that in Letters Patent No. 823,586, granted June 19, 1906, upon the application of Eugene F. Davenport, of Melrose, Massachusetts, for an improvement in "Skiving-Machines," an error appears in the printed specification requiring correction, as follows: In line 65, page 3, the word "and" should be stricken out and inserted before the clause "a feeding-disk shaft" in same line; and that the Letters Patent should be read with this correction therein that the same may conform to the record of the case in the Patent Office.

Signed and sealed this 28th day of August, A. D., 1906.

Acting Commissioner of Patents.

ing device to be retarded by resistance applied to said device without changing the speed of the cutter.

12. In a skiving-machine, the combination with a cutter, a work-feeding device, and actuating means connected with the cutter and the feeding device to drive said devices normally at predetermined relative speeds, of a frictional connection located between the feeding device and said actuating mechanism

and arranged to allow the operator to retard the movement of the feeding device by holding back the work.

In testimony whereof I have signed my name to the specification in the presence of 15 two subscribing witnesses.
